SAFE

Felix Danninger and Edward J. Kastenholz,
Milwaukee, Wis., assignors to The Bergs
Manufacturing Company, Milwaukee, Wis.

Application February 20, 1937, Serial No. 126,867

1 Claim. (Cl. 109—3)

This invention appertains to safes or strong-boxes, and more particularly to a novel device especially adaptable for use as a tabernacle for church altars, and is of the same general character as that shown in Patent No. 1,944,430, issued to Anton Hofer and Felix Danninger, January 23, 1934.

In the above-mentioned patent a key-operated shaft for a pair of doors is shown, and this shaft, through a spiral groove and pin connection, is given a longitudinal movement during the turning thereof by the key for operating certain door-latching members.

The use of double doors in said patent is relatively expensive, but due to the weight of a single door, the same could not be advantageously used.

It is, therefore, one of the primary objects of our present invention to provide novel means for utilizing a single door and for counter-balancing the weight of the door, whereby the door will be easy to operate, and undue strain will be eliminated from the door hinges.

Another salient object of our invention is to provide a novel mechanism operated from the main shaft for effectively latching the door in its closed position, both from the top and bottom thereof, whereby unauthorized entrance into the tabernacle will be prevented.

A further important object of our invention is to provide a simple and inexpensive mechanism for latching a swinging door in a closed position from a key-controlled shaft.

With these and other objects in view the invention consists in the novel construction, arrangement, and formation of parts, as will be hereinafter more specifically described, claimed, and illustrated in the accompanying drawings, in which drawings:

Figure 1 is a top plan view of our improved safe.

Figure 2 is a rear elevation of the same.

Figure 3 is a bottom plan view of the safe.

Figure 4 is a view similar to Figure 3 showing the door in its open position.

Figure 5 is an enlarged, fragmentary, detail sectional view taken on the line 5—5 of Figure 3, looking in the direction of the arrows, illustrating the means for operatively connecting the key-operated shaft with the latching mechanism.

Figure 6 is an enlarged, fragmentary, longitudinal sectional view through the operating shaft taken substantially on the line 6—6 of Figure 3, looking in the direction of the arrows, showing the operative connection between said shaft and the door-latching mechanism.

Figure 7 is a detail section through the shaft

taken substantially on the line 7—7 of Figure 6, looking in the direction of the arrows.

Figure 8 is a detail section through the shaft taken on the line 8—8 of Figure 7, looking in the direction of the arrows.

Referring to the drawings in detail, wherein similar reference characters designate corresponding parts throughout the several views, the letter A generally indicates our improved altar safe.

The safe includes a body 10 formed from steel or the like, and the same is of the identical type illustrated in the mentioned patent. Thus, the body 10 includes top and bottom walls 11 and 12, and side and rear walls 13. The side and rear walls 13 can be formed from a single piece of metal, if so desired, and all of the walls are united by tie rods 14, which extend through the top and bottom walls 11 and 12.

The front of the safe body 10 is left open so that access can be had to the interior of the body, and this open front is normally closed by an arcuate door 15, which conforms to the arcuate configuration of the body. The safe is adapted to be set into an altar and the door 15 can be of an ornamental character, if so desired. As illustrated, the top and bottom walls can carry feet 16 for spacing the safe from the adjacent parts of the altar.

In accordance with our invention, the upper and lower edges of the door 15 have rigidly secured thereto inwardly extending top and bottom hinge leaves 17 and 18. These leaves 17 and 18 lie in close parallel relation to the top and bottom walls of the safe, and the inner ends thereof are rotatably mounted on suitable stub shafts 19 carried by the top and bottom walls of the safe.

The bottom leaf 18 is provided with a sector gear 20, the purpose of which will be later set forth.

The upper leaf 17 has rigidly secured thereto the rearwardly extending arm 21, the outer end of which carries a weight 22. This weight 22 functions to counterbalance the weight of the door 15 and thereby reduce undue strain on the hinge leaves and the stub shafts 19.

In order to guide the door 15 during its opening and closing movement, the door has formed on or secured to its upper and lower edges, arcuate guide bars 23, which engage the top and bottom of the safe body when the door is swung to its fully opened position.

The mechanism for operating the door 15 is the same as the mechanism for operating the pair

of doors illustrated in the patent referred to, and thus we provide an operating shaft 24 including a front section 25 and a rear tubular section 26. The rear tubular section is held 5 against longitudinal movement but rotates freely in bearings 27 carried by the lower wall 12 of the same. The rear end of the shaft has formed thereon or keyed thereto a beveled pinion 28, which meshes with the sector gear 20 on the 10 hinge leaf 18, so that upon the turning of the shaft the door will be swung to an open or closed position, depending upon the path of rotation of said shaft.

The forward end of the shaft section 24 is 15 provided with a screw thread or a spiral groove 29 into which is fitted a pin (not shown) carried by a guide bracket and a bearing 30 on the lower wall of the body. Thus, on rotation of the shaft section 24, the same will be moved inwardly and 20 outwardly due to the pin and slot connection.

In order to impart rotary movement to the shaft section 26 from the shaft section 25 without moving the shaft section 26 longitudinally, the inner end of the shaft section 25 carries a 25 cross-pin 31, which is received in longitudinal slots 32 formed in the shaft section 26.

A pin-and-tumbler lock 33 is provided for normally holding the shaft section 25 against movement, and a key 34 is provided for operating the 30 pins of the lock, so that upon insertion of the key into the shaft, the shaft can be rotated by the key.

As previously stated, the construction of the shaft and its lock is the same as that shown and 35 described in the mentioned patent, and hence details of the lock and mounting of the shaft have not been fully illustrated.

In accordance with our present invention we 40 provide a thrust collar 35 for the operating shaft, and this thrust collar is joined to the shaft section 25 by the cross-pin 31. Hence, the thrust collar moves longitudinally with the shaft.

The thrust collar is preferably formed from independent ring sections 36, 37 and 38. The ring section 38 receives the pin 31, and hence said 45 ring section 38 turns with the shaft 24. The ring section 37 carries outwardly extending pins 39, which are independent of the ring section 38, and hence no turning movement is imparted to 50 the ring section 37 or its pins 39. The ring sections 36 and 38 lie on opposite sides of the ring section 37, and these ring sections constitute bearing members for engaging arms 39' and 40 of a swinging latch member 41, which will be 55 described in detail.

It is to be noted, however, that the arms 39 and 40 of the latch member snugly engage the outer faces of the ring sections 36 and 38 of the collar and hold all of the ring sections in contact with one another against lost motion. These 60 arms 39 and 40 can be provided with bearing ears 42 for engaging the adjacent ring sections.

Referring to the swinging latch 41, the same 65 preferably consists of inner and outer plates 43 and 44, which are centrally apertured to form the arms for straddling the collar, and these plates at one end are pressed together and rigidly secured by rivets or the like. This end of the latch is rotatably mounted on a pivot pin 45 carried by a boss 46 on the bottom plate 12. The 70 opposite end of the plate 44 has formed thereon a latch hook 47 for engaging a keeper pin 48 carried by the hinge leaf 18 of the door 15.

From the description so far it can be seen 75 that when the shaft is released by the key 34 and

the shaft is turned in a counter-clockwise direction (see Figures 3 and 4), the door will be swung to an open position. However, prior to the turning movement of the shaft section 26 longitudinal movement is imparted to the shaft section 25 through the spiral slot and pin connection heretofore referred to. Hence, the collar 35 will be slid longitudinally, swinging the latch 41 away from the keeper pin 48. Continued 10 rotating movement of the shaft will open the door.

When the key is turned in a reverse direction the door will be moved to its closed position, and when the door reaches this closed position, the shaft section 25 will be slid forwardly carrying 15 the collar 35 therewith and thereby moving the latch 41 to its hooked position with the pin 48.

It is desirable to latch the door 15 from the top as well as the bottom, and hence we have provided a latching mechanism 49 for the top 20 of the door. This latching mechanism 49 is operated from and in synchronism with the operating means for the latch 41 for the bottom of the door.

The latch mechanism 49 for the top of the 25 door includes a double-armed latch lever 50 rotatably mounted intermediate its ends on a pivot pin 51 carried by the top wall 11 of the safe body. The opposite ends of the latch lever 50 carry hooks 52 and 53 respectively, and these 30 hooks are adapted to engage a latch pin 54 on the top hinge leaf 17 and a stop pin 55 on the safe when the door 15 is in its closed position.

Pivotedly secured to the latch lever 50 at one side of the pivot pin 51 is a connecting link 56, 35 which extends longitudinally of the safe. The rear end of the link 56 is pivotally connected to a crank lever 57 rigidly secured on a vertically disposed shaft 58 carried by suitable bearings, and this shaft 58 is arranged at the rear of the 40 safe, and has rigidly connected to its lower end a crank-arm 59. The crank-arm 59 has pivotally secured thereto a forwardly extending rod 60. The rod 60 is mounted in suitable guideways 61, and the forward end thereof carries a yoke 62, 45 the arms of which are operatively connected to the radially extending pins 39 carried by the intermediate ring section 37 of the collar 35.

Obviously, through this connection, when longitudinal movement is given the collar 35 in a 50 rearward direction the rod 60 will rock the shaft 58, which will in turn rock the latch lever 50 through the link lever 56. Upon forward sliding movement of the collar 35 the latch lever 50 will be returned to its normal latched position. 55

From the foregoing description it can be seen that we have provided an exceptionally simple and durable mechanism for mounting a single door on a tabernacle safe and for latching the door against unauthorized movement. 60

Changes in details may be made without departing from the spirit or the scope of our invention, but what we claim as new is:

Door moving and locking mechanism for tabernacle safes and the like comprising, in combination, a swinging door, inwardly extending leaves secured to the upper and lower edges of the door, an operating shaft for opening and closing the door, key-actuated means for operating the shaft, said shaft including a section 65 having rotatable and longitudinal movement, a collar movable longitudinally with the shaft section including independent rings, one of which is non-rotatable relative to the shaft section, and another one of which is rotatably connected with 70 75 80 85 90 95 98

the mentioned ring, top and bottom swinging latch levers, latch pins carried by the leaves, latch hooks on the latch levers for engaging the pins when the door is in its closed position, one of said latch levers having spaced arms straddling the collar, whereby upon longitudinal movement of the collar the latch will be actuated therewith, the other of said latch levers having a link pivotally connected therewith, a

rockably mounted vertical shaft secured thereto, said shaft having crank-arms secured thereto, an operating rod, means operatively connecting the link and the rod to the crank-arms, and means connecting the rod with the second-mentioned ring of the collar. 5

FELIX DANNINGER.
EDWARD J. KASTENHOLZ.
